CLAIM

The ornamental design for a mascara container, as shown and described.

DESCRIPTION

FIG. 1 is a perspective view from above of the mascara container.

FIG. 2 is another perspective view from above of the mascara container of FIG. 1.

FIG. 3 is a perspective view from below of the mascara container of FIG. 1.

FIG. 4 is a front elevation view of the mascara container of FIG. 1.

FIG. 5 is a rear elevation view of the mascara container of FIG. 1.

FIG. 6 is a left side elevation view of the mascara container of FIG. 1.

FIG. 7 is a right side elevation view of the mascara container of FIG. 1.

FIG. 8 is a bottom plan view of mascara container of FIG. 1.

FIG. 9 is a top plan view of the mascara container of FIG. 1; and,

FIG. 10 is an enlarged view of FIG. 9, showing the top plan view of the mascara container of FIG. 1.

The broken lines in FIGS. 3 and 8 illustrate portions of the mascara container that form no part of claimed design.

1 Claim, 7 Drawing Sheets
